STRIP ADVANCING MEANS FOR COUNTING AND RECORDING MECHANISMS

James F. Bowers, Memphis, Tenn., assignor of
forty-nine per cent to Daniel N. Copp and
Richard O. Wilson

Original application May 25, 1950, Serial No.
164,091. Divided and this application August
20, 1951, Serial No. 242,773

8 Claims. (Cl. 101—96)

1

This invention relates to certain new and useful improvements in means for synchronized strip advancement adapted particularly for use with printing means associated with counting and recording mechanisms. More particularly this invention relates to means for advancing strips such as elongated paper for receiving printed records and inking ribbons used therewith in synchronism with the printing motion of the printing means, the present means being activated by the motion imparted to the printing means. This invention further relates to strip advancing means which are so constructed and arranged as to effect disengagement after predetermined advancement to prevent undesired shift or advancement of the strip means.

This application is a division of co-pending application, Serial No. 164,091, filed May 25, 1950.

The principal object of the present invention is to provide in combination with printing means as for counting and recording mechanisms a novel mechanism and arrangement for effecting shift of a record receiving strip and of an inking strip, including means for disengaging the shifting relation after predetermined strip advancement has been accomplished.

A further object of the invention is to provide in combination with an oscillatable assembly for supporting and moving a record receiving strip and an inking strip into printing engagement with indicia bearing means, pawl and ratchet means effective upon assembly oscillation to shift the strips, which include pawl-carried means for camming by engaging the ratchet means to effect disengagement of the pawl means from the ratchet means to interrupt such shift.

A further object of the invention is to provide in a ratchet engaging pawl a cam portion for contacting the periphery of the ratchet during swinging movement of the ratchet to interrupt pawl engagement.

A further object of the invention is to provide a new and novel arrangement of strip shifting means, including means for interrupting such shifting.

A further object of the invention is to provide, in combination with counting means having printing record receiving means, means for shifting the record receiving means of a new and novel character.

A further object of the invention is to generally improve the design, construction and efficiency of strip shifting means for use in connection with record printing means.

The means by which the foregoing and other objects of the present invention are accomplished

2

and the manner of their accomplishment will readily be understood from the following specification upon reference to the accompanying drawings, in which:

5 Fig. 1 is a front view of a counting and recording mechanism, incorporating the present invention with the front wall removed for purposes of illustration.

10 Fig. 2 is a view similar to Fig. 1, illustrating the present invention with the printing mechanism in lowered rest position.

15 Fig. 3 is a fragmentary front view with certain parts removed for illustration.

Referring now to the drawings, the present invention is preferably housed in a casing, including a top 21, bottom 22, rear wall 23, and side walls 24, 25, with closure of the front of the device being preferably effected by a retainer wall 26 which extends from top to bottom and side to side.

20 The front and rear walls are interconnected by upper and lower bars which extend respectively through the front and rear walls and are preferably secured in place by suitable nuts, these bars including upper bars 29.

25 The present invention is illustrated in conjunction with a counting and recording mechanism of the character described in the above mentioned co-pending application, which includes a plurality of number wheels 81, each provided with embossed or raised figures mounted as upon a shaft 73.

30 Mounted in the casing and underlying the number wheels is the printing mechanism, which includes a pan 151 disposed transversely of the casing and supported adjacent one side of the casing by a rod 153 extending between and secured to the front and rear retainer walls 26, 27. Rod 153 passes through a pair of opposite substantially vertically disposed flanges 155 forming the front and rear portions of pan 151, and the pan is rockably supported upon rod 153 as a pivot. The top of the pan is formed of a flat plate-like member 157 which extends between flanges 155 and 35 from which flanges 155 depend. Adjacent the pivot rod 153, top plate 157 is continued in a downwardly and transversely extending arcuate portion 159 adapted to serve as a support for a roll of record receiving strip, such as paper 161 at one side of pan 151. At its remote end roll support 159 is preferably provided with a resilient member 171 which is adapted to overlie and contact one side of paper roll 161 and by its resiliency is urged into contact so as to serve as a retainer 40 for the paper roll.

45 Depending pan flanges 155 are continued be-

beyond the arcuate roll support portion 159 of pan top 151 by sections 173, flange sections 173 respectively lying along the front and rear of supporting section 159 and serving as limits against forward or rearward movement of paper roll 161. Pan plate 157 extends in the opposite direction beneath number wheels 81, and beyond the number wheels is provided with a transverse slot 175 which is adapted to receive and have threaded therethrough a length of strip 176 from paper strip roll 161. Beyond slots 175, pan 151 is provided with a cover portion 177 which is preferably offset upwardly from the plane of plate 157 and otherwise extends between and is secured to pan flanges 155.

Intermediate the length of pan flanges 155 an abutment, preferably a bar 179 forming part of the pan assembly preferably is provided, the bar extending between and being rigidly secured to the respective front and rear pan flanges. Abutment bar 179 is positioned to lie vertically beneath the axis of shaft 73 by which the number wheels are carried. Substantially midway of the length of pan 151 a resilient platen member 181, as of rubber or similar material, is fixed to the upper face of pan plate 157 and extends from front to rear thereof underlying number wheels 81, and lying between the pan plate and the number wheels. Underlying cover member 177 and substantially in engagement therewith are a plurality of friction rollers 183, mounted upon and secured to a shaft 185 journalled in pan flanges 155. Rollers 183 are adapted to serve as feed rollers for paper strip 176 from paper roll 161 and the rollers and cover 177 are arranged so that paper strip 176 may be fed therebetween and the frictional engagement of the underside of paper strip 176 by the friction rollers against the underside of cover 177 enables the rollers upon rotation of shaft 185 to effect advancement of the paper 176.

Below pan 151 and in vertical alignment with shaft 73 and pan bar 179, a shaft 189 is journalled in front and rear retainer walls 26, 27. Carried by and fixed to shaft 189 are front and rear cam members 191 which underlie and support pan bar 179 effecting support of pan 151 intermediate its length. Intermediate front and rear cam members 195 are positioned respectively rearwardly and forwardly of front and rear cams 191 and are independently supported from shaft 189. To one of the cams 195, an arm 197 is integrally secured, which are, at its lower end, is coupled to the armature of a solenoid 199. Solenoid 199 is preferably rockably mounted upon a rod 201 secured to and extending between front and rear retainer walls 26, 27, and solenoid 199 is further coupled electrically, as by leads 203, to a source of energization. One end of tension spring 205 is coupled to cam arm 197, the opposite end of the spring being suitably attached to the casting as by attachment to a bar 207 and consequently urges movement of arm 197 toward bar 207.

A pair of ink ribbon rolls 208 are turnably supported by brackets 209, 210 above the level of pan 151, brackets 209, 210 being preferably attached to pan flanges 155. A ribbon strip 211, inked in conventional fashion, which is carried by the ribbon rolls 208, passes beneath the number wheels 81 and overlies paper strip 176 from paper roll 161, paper strip 176 being interposed between ribbon strip 211 and platen member 181. Ribbon rolls 208 are each suitably supported upon

rods or shafts journalled respectively in brackets 209, 210.

5 Adjacent forward pan flange 155 and lying between the pan flange and knob 187 a ratchet 219 is fixed to feed roll shaft 185. A pawl 221, pivoted upon a pin 233 carried by forward wall 26, is urged toward engagement with ratchet 219 by a spring 225, and normally lies in engagement with the teeth of ratchet 219 and is adapted to maintain pawl engagement with ratchet 219 so as, upon upward movement of pan 151, to effect rotation of feed roll shaft 185 and rollers 183 carried thereby, thus effecting advancement of paper strip 176 from roll 161 during pan raising. 10 Pawl 221 is provided with a cam in the form of an intermediate enlarged bulge portion 221A which is bulged toward feed roll shaft 185 and ratchet 219 so that upon continued upward movement of pan 151, beyond paper strip advancement, ratchet 219 is moved into contact with bulge portion 221A of pawl 221, thereby cammingly removing pawl 221 from engagement with ratchet 219, interrupting the advancement of paper strip 176.

25 A pawl 227, pivotally mounted upon a pin 229 also secured to front wall 26, normally lies in engagement with a ratchet 231, carried by the ribbon roll shaft which is journalled in bracket 210. Ribbon roll pawl 227 is formed similarly to pawl 221 of the paper feed to include a cam in the form of an enlarged bulge portion 227A and is urged by a spring 233 into engagement with ratchet 231 in normal position of pan 151. Ratchet 231 is carried forward of bracket 210 and between that bracket and front wall 26. The ribbon roll pawl and ratchet arrangement is adapted similarly to the paper strip feed pawl and ratchet arrangement to effect advancement of the ribbon strip 211 upon upward movement of pan 151 and as the pan is continued in its upward movement ratchet 231 is moved into contact with pawl cam portion 227A, camming pawl 227 out of engagement with ratchet 231, thereby interrupting the advancement of ribbon strip 211.

45 In the employment of the printing mechanism solenoid 199 is normally positioned in deenergized condition with its armature extended. Upon energization of solenoid 199 through leads 203, as upon the occurrence of the energization 50 of the machine or other instrumentality with which the mechanism is employed, the solenoid armature is retracted in conventional fashion moving through the position shown in Fig. 1 to the position shown in Fig. 2. As the solenoid 55 armature is thus retracted, cam arm 197 is moved therewith effecting rotation of cams 195, which cams acting upon pan 151 through bar 179 effect raising of the bar and of the pan 151 to which the bar is rigidly fixed, moving pan plate 157, platen 181, and paper strip 176 upwardly, bringing the paper into underlying contact with ribbon strip 211 and moving thence into engagement with the raised figures carried by the number wheels 81. In this manner a print is made of the record at 60 the instant upon which the mechanism or machine with which the instrumentalities are being employed is first energized. Similarly at the end of the run or upon other deenergization of the machine or other instrumentality with which the present invention is being employed occurs, solenoid 199 upon such deenergization releases its 65 retracting action upon its armature, and arm 197 is returned by tension spring 205 to its initial position with the armature of the solenoid extending 70 75 ed. As the arm 197 is thus returned by spring

205, cams 195 are again moved beneath bar 179 and again effect upward movement of the bar and of pan 151, again effecting printing of the record as it exists at the time of such deenergization.

If normal printing is desired shaft 189 may be rotated causing cams 191 to act upon bar 179 raising pan 151 and paper strip 176 into printing position, the existing record being thus printed on paper strip 176.

It will be seen that in each instance printing is accomplished by cam raising or oscillation of pan 151 to carry paper strip 176 into printing engagement with ribbon strip 211 and the number wheels. In the manner described above shift of the ribbon strip 211 and of paper strip 176 is accomplished on each raising of pan 151 through the engagement of ratchet 231 with pawl 227 and of ratchet 219 with pawl 221. It will be seen that this paper and ribbon shift is accomplished, as described, during the initial portion of pan raising and is completed prior to printing contact, the pawls being disengaged by the interaction of the pawl cams 227A and 221A respectively with the periphery of the ratchets so that further shift is prevented until the pan has been returned to normal lowered position for subsequent operation, at which time cam engagement with the ratchets is broken and springs 225, 233 are effective to move the respective pawls into engagement with the teeth of the respective ratchets for subsequent operation.

It is apparent that other variations in detail of structure may be substituted for instrumentalities depicted and described herein without departing from the invention involved.

It will be understood that the forms of the devices embodied in the drawings attached hereto are intended to be illustrative of the example of the invention chosen for the purposes of this disclosure, and that it is the purpose of this application to cover all such changes and modifications in this example which do not constitute departure from the spirit and scope of the invention embodied herein.

I claim:

1. In a device which includes indicia bearing means, a member, having a plate portion, rockably supported below said means for vertical movement toward and away from engagement with said means, means carried by said member at one side thereof for supplying a strip of inking ribbon and a strip of paper to extend between said plate portion and said indicia means, strip shifting means disposed at the opposite side of said member comprising rotatable strip engaging means carried by said member, ratchet means coupled to said rotatable means, pawl means, means independent of said member supporting said pawl means in engagement with said ratchet means, said ratchet means and said rotatable means being moved with said member, said pawl means acting with said ratchet means during rocking movement of said member toward engagement with said indicia means to effect rotation of said strip engaging means and strip shift, said pawl means being bulged with the bulge lying in the path of the periphery of said ratchet means during member movement toward engagement with said indicia means, the bulge of said pawl means being engaged by the periphery of said ratchet means upon movement of said member beyond said strip shift to cam said pawl means out of acting engagement with said ratchet means to interrupt said strip shift, prior to 75

completion of member movement toward said indicia means.

2. In a device which includes indicia bearing means, a member, having a plate portion, rockably supported adjacent said means for movement toward and away from engagement with said means, rolls carried by said member at one side thereof for respectively supplying a strip of inking ribbon and a strip of paper to extend between said plate portion and said indicia means, strip shifting means disposed at the opposite side of said member comprising upper and lower rotatable strip engaging means carried by said member, ratchet means carried by said member and coupled to said rotatable means, upper and lower pawl means, means independent of said member supporting said pawl means in engagement with said ratchet means, said pawl means acting with said ratchet means during rocking movement of said member toward engagement with said indicia means to effect concurrent rotation of said strip engaging means and strip shift, said pawl means being bulged with the bulge lying in the path of the periphery of said ratchet means during member movement toward engagement with said indicia means, the bulge of said pawl means being engaged by the periphery of said ratchet means upon movement of said member beyond said strip shift to concurrently cam said pawl means out of acting engagement with said ratchet means to interrupt said strip shift, prior to completion of member movement toward engagement with said indicia means.

3. Ribbon feed means for use in a device which includes printing means, plate means beneath said printing means for supporting an overlying tape-like record strip to receive printing from said printing means, means respectively positioned on opposite sides of said printing means, 35 to support an inked ribbon between a supported said record strip and said printing means, and means rockably supporting said strip-supporting means for swinging movement into engagement with said printing means, said feed means comprising rotatable means associated with said ribbon supporting means, a ratchet mounted on said rotatable means, a pawl, means pivotally supporting said pawl in engagement between the teeth of said ratchet to effect rotation of said 40 rotatable means and advancement of said ribbon upon swinging movement of said plate toward and prior to engagement with said printing means, said pawl including a bulged portion positioned at an intermediate point in the path of the teeth of said ratchet to abut the periphery of said ratchet during continuation of said plate swinging movement, said abutment being effective to cam said pawl out of ratchet advancing engagement to interrupt ribbon advancement.

4. Ribbon roll feed means for use in a device which includes printing means, plate means beneath said printing means for supporting an overlying tape-like record strip to receive printing, ribbon rolls respectively positioned on opposite sides of said printing means to support an inked ribbon between a supported said record strip and said printing means, and means rockably supporting said strip-supporting means for swinging movement into engagement with said printing means, said ribbon roll feed means comprising a shaft attached to and supported by said strip supporting means, one of said ribbon rolls being mounted on said shaft, a ratchet mounted on said shaft, a pawl, means pivotally supporting said pawl in engagement between the teeth of

said ratchet to effect advancement of said ribbon rolls upon initial swinging movement of said plate toward engagement with said printing means, said pawl including a bulged portion positioned at an intermediate point in the path of the teeth of said ratchet to abut the periphery of said ratchet during continuation of said plate swinging movement, said abutment being effective to cam said pawl out of ratchet advancing engagement to interrupt ribbon roll advancement.

5. Record strip feed means for use in a device which includes printing means, plate means for supporting an overlying tape-like record strip to receive printing, and means rockably supporting said strip-supporting means for swinging movement into engagement with said printing means, said record strip feed means comprising a cover connected to said plate means, a strip receiving slot positioned at a junction of said cover and said plate for the insertion of a record strip therethrough to underlie said cover, a shaft attached to and underlying said cover adjacent said slot, feed roll means carried by said shaft and positioned to frictionally engage an inserted record strip, a ratchet mounted on said shaft, a pawl, means pivotally supporting said pawl in engagement between the teeth of said ratchet to effect advancement of said feed roll means upon swinging movement of said plate means toward engagement with said printing means, said pawl including a bulged portion, positioned at an intermediate point in the path of the teeth of said ratchet to abut the periphery of said ratchet during continuation of said plate swinging movement, said abutment being effective to cam said pawl out of ratchet advancing engagement to interrupt feed roll advancement.

6. Record strip feed means for use in a device which includes printing means, means for supporting a tape-like record strip to receive printing, and means rockably supporting said strip-supporting means for swinging movement into engagement with said printing means, said record strip feed means comprising feed roll means positioned to frictionally engage said record strip, a shaft supporting said feed roll means, a ratchet mounted on said shaft, a pawl, means pivotally supporting said pawl in engagement between the teeth of said ratchet to effect advancement of said feed roll means upon swinging movement of said strip supporting means toward engagement with said printing means, said pawl including a bulged portion, positioned in the path of the teeth of said ratchet to about the periphery of said ratchet during continuation of said swinging movement, said abutment being effective to cam said pawl out of ratchet advancing engagement to interrupt feed roll advancement.

7. Strip advancing means for use in a device which includes printing means, plate means for supporting an overlying tape-like record strip to receive printing, means supporting an inked ribbon strip between a supported said record strip and said printing means, and means rockably supporting said plate means for swinging upward movement into engagement with said printing means, said strip advancing means including

record strip feed means and ribbon strip feed means, said record strip feed means comprising a cover connected to and forming a continuation of said plate means offset above the level of said plate means, a strip receiving slot positioned at the junction of said cover and said plate for the insertion of said record strip therethrough to underlie said cover, a shaft attached to and underlying said cover adjacent said slot, feed roll means carried by said shaft and positioned to frictionally engage an inserted record strip, a second shaft attached to and spaced above said plate means, part of said ribbon feed means being mounted on said second shaft, each said shaft having a ratchet mounted thereon, pawls respectively pivotally supported in engagement between the teeth of said ratchets to effect concurrent rotation of said shafts and advancement of said record and ribbon strips upon upward swinging movement of said plate toward engagement with said printing means, said pawls each including a bulged portion positioned in the path of the teeth of its related said ratchet to abut the periphery of said related ratchet during continuation of said plate swinging movement, said abutment being effective to concurrently cam said pawls out of ratchet advancing engagement to interrupt record and ribbon strip advancement, prior to engagement with said printing means.

30 8. In a printing device, a substantially horizontal plate, means supporting said plate for vertical swinging movement, a ribbon windup spool, a shaft supporting said spool, said shaft carried by and spaced above said plate, a ratchet fixed to said shaft, a pawl, fixed pivot means supporting said pawl, said pivot means being above the level of said shaft and said pawl depending into engagement with the teeth of said ratchet, spring means engaging and urging said pawl toward ratchet engagement, said pawl including a curved cam portion, upward swinging movement of said plate moving said ratchet upwardly causing ratchet rotation while engaged with said pawl during an initial portion of said swinging movement, said ratchet moving into engagement with said cam portion upon continuation of said movement and prior to completion thereof, engagement between said cam portion and ratchet shifting said pawl and interrupting ratchet rotation 40 prior to completion of said swinging movement.
